CLAIM

The ornamental design for a headwear article as shown and described.

DESCRIPTION

FIG. 1 is a left side view of a headwear article according to our new design;

FIG. 2 is a right side view thereof;

FIG. 3 is a front view thereof;

FIG. 4 is a rear view thereof;

FIG. 5 is a top view thereof; and,

FIG. 6 is a bottom view thereof.

The long-dash broken lines in the drawings illustrate portions of the headwear article that form no part of the claimed design.

The short-dash broken lines in the drawings represent stitching that forms no part of the claimed design.

1 Claim, 6 Drawing Sheets
